UNITED STATES PATENT OFFICE.

JOSIAH F. FRENCH, OF PHILADELPHIA, PENNSYLVANIA.

FILE AND OTHER TOOLS HAVING TAPERING TANGS.

SPECIFICATION forming part of Letters Patent No. 285,989, dated October 2, 1883.

Application filed August 27, 1883. (No model.)

To all whom it may concern:

Be it known that I, JOSIAH F. FRENCH, a citizen of the United States, residing in Philadelphia, Pennsylvania, have invented a certain Improvement in Files and other Tools having Tapering Tangs, of which the following is a specification.

My invention relates to files or other tools which are provided with tapering tangs adapted to be driven into wooden handles; and the object of my invention is to so thread the tapering tang of a tool of this class that a handle of which a nut forms a part may be screwed on and unscrewed from the tang, the thread 15 of the latter being at the same time such as not to interfere with the driving of the tang into an ordinary handle in the absence of a special handle.

In the accompanying drawings, Figure 1 is 20 a side view of part of a flat file having a tapering tang made according to my invention; Fig. 2, a transverse section on the line 1 2; Fig. 3, a sectional view of a handle adapted to the tang, and Fig. 4 a modification of the invention.

My invention may be applied to any file or other tool provided with a tapering tang—a chisel, for instance—and it is not intended to alter or modify the tang as regards general shape, excepting in the particulars explained 30 hereinafter, for while it is made to screw into a nut embedded in a special handle, it must be such that it can be driven into an ordinary handle in the usual way.

A portion, *a*, of the tapering tang *A* is 35 threaded, the thread extending in the present instance over the opposite edges only, as shown in Fig. 2; and this threaded portion of the tang is adapted to the internally-threaded part *x* of a tube, *D*, which is driven into the wooden 40 portion *B* of a handle, so that on screwing the latter onto the tang the end of the tube *D* may be brought to bear on shoulders *m m* of the tool, or against the edges of the tang, thereby firmly securing the handle to its place.

It should be understood that the handle 45 forms no part of my present invention, and that any handle in which is a nut adapted to the threaded portion of the tang may be applied to the same.

The tang must be parallelly threaded—that 50 is to say, a dotted line, *f*, indicating the bottom of the thread on one edge of the tang, must be parallel with the dotted line *t'*, indicating the bottom of the thread on the opposite edge 55 of the tang, for to make the thread on a taper

would interfere with the proper tightening of the end of the handle to its bearing.

The tang should always terminate in a plain portion, *b*, for if the screw-thread should be continued to the extreme end of the tang it 60 would interfere with the proper driving of the same into an ordinary handle, and this might often be required in the absence of a special handle. For the same reason it is always best to confine the thread within the limits 65 indicated by the dotted line *w w*, coinciding with the inclined edge of the tang, this, of course, involving the necessity of making the thread gradually shallower as it approaches the end of the tang; but the thread is none 70 the less parallelly cut and adapted to the parallelly-cut thread *x* in the tube *D* of the handle.

A perfect parallelly-cut thread adapted to the internal thread, *x*, of like character, may 75 be made on a tapering tang, as shown in Fig. 4; but the tang in this case also should terminate in a plain tapering portion, *b*, to be driven into the wood of an ordinary handle, *B*, the orifice in which is made to avoid the threaded 80 portion of the tang.

The invention is not restricted to the tangs of flat files or chisels, for the desired thread may be cut on the tapering tang of a square, round, or triangular file, or, indeed, on the tapering tang of any other tool.

I am aware that a tapering thread has been cut on a tapering tang for screwing into and permanent attachment to a block externally threaded for screwing into a wooden handle; but it is essential to my invention, as before remarked, that the tang should be parallelly threaded.

The handle *D* is hereby disclaimed in this application, as it forms the subject of another 95 application for a patent filed by me August 24, 1883, Serial No. 104,634.

I claim as my invention—

As a new manufacture, a file or other tool having a tapering tang, on a portion, *a*, of which a screw-thread is parallelly cut, the tang terminating in a plain tapering portion, *b*, as set forth.

In testimony whereof I have signed my name to this specification in the presence of two sub- 105 scribing witnesses.

JOSIAH F. FRENCH.
